Patented May 9, 1922.

UNITED STATES PATENT OFFICE.

ALBERT LOVELESS, OF ABERDEEN, WASHINGTON.

VALVE-GRINDING TOOL.

1,415,592.

Specification of Letters Patent.

Patented May 9, 1922.

Application filed May 16, 1921. Serial No. 469,771.

To all whom it may concern:

Be it known that I, ALBERT LOVELESS, a citizen of the United States, and a resident of Aberdeen, in the county of Grays Harbor 5 and State of Washington, have invented certain new and useful Improvements in Valve-Grinding Tools, of which the following is a specification.

My invention relates to tools for grinding 10 the valves of internal combustion engines, and the purpose of my invention is the provision of such a tool which is constructed to permit of its being supported directly on the engine and readily operated therefrom to 15 accomplish the effective grinding of the valves.

It is also a purpose of my invention to provide a valve grinding tool which is adjustable to vary the pressure exerted on the 20 valve during the grinding operation.

I will describe one form of valve grinding tool embodying my invention and will then point out the novel features thereof in 25 claims.

25 In the accompanying drawings:

Figure 1 is a view showing in perspective a conventional form of internal combustion engine with the cylinder head removed and showing applied thereto one form of valve 30 grinding tool embodying my invention.

Figure 2 is an enlarged detail perspective view of the tool shown in Figure 1.

Figure 3 is a vertical sectional view of a 35 portion of the tool shown in the preceding views showing the adjusting means of the tool for varying the pressure exerted upon a valve.

Referring specifically to the drawings, in 40 which similar reference characters refer to similar parts, my invention in its present embodiment comprises a supporting yoke Y formed of spring steel of substantially U-shaped formation with the longer arm 15 thereof formed with an opening 16 adjacent its free end, while the short arm 17 is secured thereto by means of a rivet 18 and an extension or arm 19 also formed of spring steel. The extension 19 is secured in overlapped relation with respect to the arm 17 45 and as a further additional securing means I provide a band 20 of non-resilient material which is arranged in embracing relation with respect to the extension 19 and the arm 17 in the manner clearly shown in Figure 2. 50 Adjacent the free end of the extension 19

an opening is provided through which I extend a screw threaded spindle S the lower end of which is formed with a disc-like head 21 carrying valve engaging pins 22 arranged at diametrically opposed points on 60 the head. The upper end of the spindle S is formed with a flat threaded extension 23 which fits in a correspondingly shaped slot formed on one end with an operating crank 24 carrying a handle 25. The crank 24 is 65 secured upon the extension 23 by means of a nut 26 and in such manner that rotation of the crank effects rotation of the spindle.

The spindle S carries thereon an adjusting nut N which threadedly engages the spindle 70 to permit of its occupying various positions along the spindle to allow of the variance in pressure exerted upon the head 21 as will be more clearly described hereinafter. The nut N is provided at its upper side with a 75 sleeve 27 which loosely fits within the opening of the extension 19 with respect to the spindle S.

In the applied position of the tool as shown in Figure 1, one of the bolts for securing the 80 cylinder head upon the engine is utilized in securing the yoke Y in vertical position upon the engine and in such manner that the head 21 will be disposed directly above one of the engine valves. With the tool in this position, 85 the spindle S is now adjusted so that the head 21 moves into contact with the valve, with the pins 22 being disposed within the usual recesses of the valve. This adjustment of the spindle S is obtained by a manipulation of the nut N, it being clear that by adjusting the nut upwardly on the spindle, the spindle and head 21 will be moved downwardly until such head engages the valve 90 with the requisite or desired degree of pressure. With the tool so adjusted, the actual grinding of the valve is obtained by oscillating the crank 24 through the medium of the handle 25, this operation causing oscillation of the head 21 with a similar movement 100 of the valve within its seat. If it is desired to increase or decrease the pressure exerted upon the valve, it will be clear that it is only necessary to adjust the nut N vertically to immediately secure the desired pressure. 105 By virtue of the fact that the yoke Y and the extension 19 are formed of spring steel, it will be manifest that they provide a resilient support for the spindle S to permit of the operator exerting the necessary pressure 110

upon the valve without permanent distortion of the tool.

When the grinding of one valve has been completed, the adjacent valve upon the opposite side of the tool can be likewise ground by loosening the cylinder head bolt and swinging the tool so that the head 21 is disposed directly over the valve whereupon the bolt is again tightened to securely hold the 10 tool in its new position.

Although I have herein shown and described only one form of valve grinding tool embodying my invention, it is to be understood that various changes and modifications 15 may be made herein without departing from the spirit of the invention or the spirit and scope of the appended claims.

What I claim is:

1. A valve grinding tool comprising a 20 yoke, an extension formed on the yoke, said yoke and extension being formed of resilient material, a screw threaded spindle loosely extending through the extension, a head formed on one end of the spindle, pins carried by said head, a reduced extension formed 25 on the other end of the spindle, a crank mounted on said reduced extension, a securing nut on said reduced extension engaging said crank, and an adjusting nut on said 30 spindle and engageable with the first extension to effect when rotated a vertical adjustment of said spindle.

2. A valve grinding tool comprising a resilient supporting yoke having one leg extended, a spindle threaded through the extended portion of the leg, a head on the one 35

end of the spindle and means for rotating the spindle.

3. A valve grinding tool comprising a resilient supporting yoke having one leg extended, a spindle threaded through the extended portion of the leg, a head on the one 40 end of the spindle, means for rotating the spindle and means co-acting with said extended leg portion for adjusting the spindle 45 vertically.

4. In combination, an internal combustion engine, a valve grinding tool comprising a yoke adapted when the cylinder head is removed to be secured upon the engine block 50 by one of the cylinder head securing bolts, an extension formed on the yoke to overlie one of the valves, a spindle rotatably mounted in said extension, a head carried by the spindle and engageable with said valve, 55 means for rotating the spindle to effect rotation of said head, and means engageable by the extension for varying the vertical position of said spindle to cause said head to engage the valve with any desired pressure. 60

5. A valve grinding tool of the character described comprising a resilient support, a rotatable spindle carried thereby, a head on the lower end of said spindle and adapted for engaging a valve to cause the valve to 65 rotate therewith, and means whereby the support may be urged upwardly with respect to the spindle and thereby force downwardly the spindle and cause pressure upon the valve with which said spindle engages for 70 the purpose described.

ALBERT LOVELESS.
